A. Randolph Jr.

Attorney

UNITED STATES PATENT OFFICE.

JOHN C. YOUNG, OF PITTSBURGH, PENNSYLVANIA.

HAIRPIN.

Application filed February 6, 1923, Serial No. 617,371. Renewed July 25, 1925.

To all whom it may concern:

Be it known that I, JOHN C. YOUNG, a citizen of the United States, residing at Pittsburgh, in the county of Allegheny and State of Pennsylvania, have invented 5 certain new and useful Improvements in Hairpins; and I do hereby declare the following to be a full, clear, and exact description of the invention, such as will enable 10 others skilled in the art to which it appertains to make and use the same.

This invention relates to a hair pin.

It is a prime object to provide a pin which will have such a grip or engagement 15 with the hair as to greatly reduce the liability, so apparent in present forms, to fall out or become accidentally displaced.

It is further aimed to provide a hair pin with one of its legs or strands having one 20 or more waves substantially parallel and adapted to coact with one or more waves of the companion leg of the pin in order to grip the hair and afford even pressure from opposite sides.

25 Additional objects and advantages will become apparent from a consideration of the description following taken in connection with accompanying drawings illustrating an operative embodiment.

30 In said drawings:—

Figure 1 is a perspective view of one form of the pin;

Figure 2 is a perspective view of another form of pin, and

35 Figure 3 is a perspective view of a third form of pin.

Referring first to Figure 1, the pin is generally designated 10 and made for instance from metallic wire in a single piece 40 or strand. As usual the pin is generally of U-shape having hair penetrating strands or legs 11 preferably parallel for a portion thereof at their penetrating ends as at 12. The pin is adapted to be gripped by the 45 fingers in the handling thereof at the bight or loop 13. Each leg 11 intermediate the portions 12 and 13 is sinuous in that it is provided with one or more convolutions or waves 14. It is to be noted that the waves 50 of one leg 11 are substantially parallel with the waves of the other leg 11. The side

portions of the legs at the loop 13 are substantially parallel with each other but disposed at an angle to the line of insertion and withdrawal of the pin so that the latter 55 will better conform to curls for concealment and will afford an effective finger grip.

In use, the pin being gripped at the loop 13 is passed into the hair as usual with the ends 12 foremost. Due to the waves 14, 60 hair is received between them, being gripped or pressed upon equally from both sides, due to the parallelism of the waves or sinuous portions of the legs 11. As a result of this construction, the pin will effectively remain in place in the hair so as not to readily fall therefrom or become displaced. As the pin is made of metallic wire, it will be readily understood that it possesses the usual resiliency of a pin of this character. 70 In other words the pin is tensioned to normally remain in the shape illustrated in the drawings and in engagement with the hair and to spring back to that normal position and thus increase the grip on the hair. 75

The form illustrated in Figure 2 is similar to that of Figure 1 except the loop 13 is displaced by a loop 15 which is rounder and larger so as to give a larger gripping surface to the fingers and also greater resiliency to the pin for yielding movement of the legs as a whole from the bight. 80

The form shown in Figure 3 may be similar to that of either form one or two except that one leg has a single wave 14 and from the same has an elongated straight portion 16 in lieu of a relatively short straight portion 12, whereby the straight portion 16 extends along and opposite a plurality of waves 14 of the companion leg. By reason 85 of this construction the hair is evenly gripped at the opposed waves but between said waves and the penetrating ends is unevenly gripped by straight portion 16 and the waves opposite it to even more effectively secure the pin against accidental displacement from the hair. 90

Various changes in the details may be resorted to provided they fall within the spirit and scope of the invention. 100

What is claimed is:—

A hair pin consisting of a strand gener-

ally of U-shape, the legs thereof having a bight of the pin substantially constituting one of the waves and being disposed substantially in parallelism and substantially angularly with respect to the line of inser- tion and withdrawal of the pin for concealing waves in spaced coacting relation, and the bight of the pin being disposed in the hair and to constitute a finger 10

JOHN C. YOUNG.
